UNITED STATES PATENT OFFICE.

NICOLAI H. HILLER, OF CARBONDALE, PENNSYLVANIA, ASSIGNOR TO CARBONDALE MACHINE COMPANY, OF CARBONDALE, PENNSYLVANIA, A CORPORATION OF PENNSYLVANIA.

CHILLING-MACHINE.

No. 922,898.

Specification of Letters Patent.

Patented May 25, 1909.

Application filed January 11, 1909. Serial No. 471,653.

To all whom it may concern:

Be it known that I, NICOLAI H. HILLER, a citizen of the United States of America, and a resident of Carbondale, county of Lackawanna, State of Pennsylvania, have invented certain new and useful Improvements in Chilling-Machines, of which the following is a specification.

My invention relates to improvements in so-called chilling machines, *i. e.*, machines such as are used in chilling paraffin and like waxes, and embodies certain improvements upon the machine for the same purpose set forth in the patent to Hatton No. 735,873, dated August 11, 1903.

My invention consists in the novel arrangement of means facilitating the removal of parts of the machine for cleaning etc., and for assembling the parts, and in various other features hereinafter described and more particularly pointed out in the claims.

Chilling machines such as herein referred to are usually constructed of a plurality of similar sections connected in series, each section comprising two concentric tubes, (the annular space between which constitutes a jacket for the flow of cooling liquid,) a spiral conveyer within the inner tube, and end connections or headers, including uptakes connecting the inner tubes of adjacent sections and downtime headers connecting the jacket spaces of adjacent sections; the cooling fluid (ammonia, brine, water etc.), commonly flowing through the jackets in a direction reverse to that of the flow of the wax through the inner tubes and corresponding uptakes. It is necessary to provide for positively forcing the solidifying wax up through the uptakes in order to prevent clogging of the machine at these points, and this I accomplish by the arrangement of the conveyer screws. It is also necessary to provide means for withdrawing the conveyer screws from time to time, also the inner tubes within which these screws revolve, and it is of course desirable to be able to remove these parts without disturbing the connections of the various sections with one another. The fulfilment of these various requirements is provided for in the machine herein illustrated and described.

The object of my invention therefore, is to provide in chilling machines, of the class referred to, for the ready removal and re-

newal of the parts, for the ready cleaning of the machine, and for the ready assemblage of the various sections of the machine, and to make the machine simple, easy to construct, assemble, clean, and operate.

Further objects of my invention will appear hereafter.

In the accompanying drawings, in which one embodiment of my invention is illustrated, Figure 1 shows a side elevation of a plurality of sections of a machine embodying my invention, one of the sections being shown in vertical longitudinal section; Fig. 2 shows a central vertical section of one of the water-circulation downtakes and adjacent parts of the machine; Fig. 3 shows an end elevation of this downtime, the glands having been removed; Fig. 4 shows a detail vertical longitudinal section of an intermediate portion of one of the sections of the machine, illustrating the manner of connection of the sections of the inner tube and of the sections of the conveyer; Fig. 5 shows a transverse section through the coupling of Fig. 4; and Fig. 6 is a detail elevation showing the thrust bearing at the end of each conveyer screw.

In said drawings, numerals 1 designate the outer tubes of the several sections and numerals 2 the inner tubes thereof, and numerals 3 the conveyer screws.

Numerals 4 designate the cooling fluid headers and numerals 5 the wax uptake headers.

As before explained, each machine consists of a number of sections of similar design, the number of sections depending upon the desired capacity of the machine. Each section is usually of considerable length—often from thirty five to forty feet over all, for which reason the tubes 1 are each commonly made of a plurality of lengths of tubing joined by couplings 6, the couplings of adjacent sections being staggered, as indicated particularly in Fig. 1; and for the same reason the inner tubes 2 are each commonly made of a plurality of lengths of tubing joined by couplings 7. The conveyer screw 3 is also made, commonly, in a similar plurality of sections, the screw being hollow, and the sections being joined, as illustrated particularly in Fig. 4, by a pin 8 projecting into the adjacent ends of the sections of the screw and connected to said sections by cross pins 9. This constitutes a rigid and satis-

factory method of joining the sections of the conveyer screw. A similar pin 10 is inserted at the thrust end of the conveyer screw and has a bearing in the cap 11 fitted at such end 5 of the header 5; and at the front or driving end of the screw another similar pin 12 is inserted having a bearing in the cap 11 at such end; such pin 12 carrying a sprocket or other gear 13 by which the conveyer may be driven. 10 Besides these end bearings the conveyer has one or more intermediate bearings in one or more bushings 14 inserted in tube 2 and commonly located opposite the coupling or couplings 7 of such tube 2. As shown particularly in Figs. 4 and 5, said coupling 7 has an 15 interior rib 15 adapted to support the bearing bushing 14, there being just sufficient clearance between said bearing bushing and shoulder 15 to permit ready insertion of the bearing bushing and to give the clearance necessary for good running. As will be seen, it is the pin 8 of the conveyer screw which has its bearing in the bearing bushing 14. The couplings 7 have outside centering lugs 20 25 fitting the inside of tube 1, these lugs comprising only a small portion of the circumference of the bushing, so that there is ample room between said lugs for the passage of the cooling fluid.

30 To permit the ready introduction of the tubes 2, with the couplings 7 thereon, through the headers 4 into the tubes 1, while providing for packing of the joint between the headers 4 and tubes 2, said headers have 35 internal ribs 17 interrupted at spaces 18 corresponding to the spacing of the lugs 16 of couplings 7; and against these ribs 17 bear steel rings 19 (Fig. 2). Packing rings 20 are inserted back of the rings 19 and the packing 40 is set up by means of a gland 21. Joints are formed between the header 4 and tubes 1 by other packing rings 22 arranged to be compressed by glands 23. The headers 5 are directly secured to flanges on tubes 2.

45 To prevent the wax clogging the uptakes in headers 5, I have found it sufficient to extend the thread on the delivery end of each conveyer past the uptake 24 in the corresponding header 5 into which that screw delivers the wax. It is not necessary to correspondingly extend the thread at the receiving end of the screw as the thread of the conveyer screw below forces the wax up through the uptake into position to be taken up by 50 the thread of the next screw.

The pin 10 at the delivery end of each conveyer screw has a reduced portion 25 projecting through a stuffing box in the corresponding header cap 11, which reduced end 60 serves to indicate whether the conveyer screw itself is rotating; for it is of course conceivable that the pins 9 through which the conveyer screw is driven might be sheared off, so that notwithstanding the rotation of 65 the corresponding driving sprocket wheel 13

and pin 12, the conveyer screw might not be rotating; but since the projecting portion 25 has no work to do the pins 9 by which it is connected to the conveyer screw, are not apt to be sheared and hence the projecting end 70 25 serves as a sure indication of whether the conveyer screw is rotating or not.

The thrust bearing at the end of each conveyer screw comprises a bronze collar 26 keyed to the pin 10, and a fiber washer 27 in 75 a recess in the header cap 11 (see Fig. 6) against which this collar 26 bears. This thrust bearing prevents the wearing of the head 11 and of the shaft of the conveyer.

In the operation of the machine it will be 80 seen that the liquid paraffin or other wax, received in the tube 2 of the bottom section of the machine, is forced through said tube by the conveyer screw therein, and up through the uptake 24 of the header 5 at the rear end of such tube to the front end of the tube 2 of the section next above, and thence is forced forward by the conveyer screw in such second tube 2 to the uptake in the header 5 at the rear end of that tube, into the tube 2 of 85 the section next above, and so on. At the same time, cooling fluid, admitted to the jacket space of the top section of the machine, flows through the said jacket space, (annular space between tubes 1 and 2), of the 90 upper section, to the downtime 28 of the corresponding header 4, and so to the jacket space of the next section, and so on; the wax being cooled progressively, therefore, as it flows through the machine, so that it is delivered from the upper section in a nearly 95 solid condition.

It is a simple matter to withdraw any conveyer screw; to do so it being necessary merely to remove the corresponding header cap 11 and pull the screw out, the bearing bushing or bushings 14 coming with it; and likewise it is a simple matter to remove any tube 2, after having first withdrawn the conveyer screw within it, by disconnecting the 100 corresponding headers 5 from that tube 2, taking out the packing between such tube and the corresponding headers 4, and then pulling the tube out through one of such headers 4, the lugs 16 of the coupling or 105 couplings of said tube 2 passing through the spaces 18 in said header 4.

While I have described the direction of flow of the wax through the apparatus as being upward, and that of the flow of cooling 110 fluid being downward, it is in a broad sense, immaterial in which direction the flow of either occurs.

What I claim is:—

1. Apparatus such as described, comprising a plurality of tubes for the flow of the material to be cooled, headers connecting them, having passages for the flow of the material from one tube to the next, screw-conveyers within said tubes, having intermediate bear- 125

ing journals, and free bearing-bushings on said journals adapted to rest against the sides of said tubes.

2. Apparatus such as described, comprising a plurality of tubes for the flow of the material to be cooled, headers connecting them, having passages for the flow of the material from one tube to the next, screw-conveyers within said tubes formed in a plurality of sections which are tubular at the ends, journal-pins seated in said conveyer sections and keyed thereto, and free bearing bushings adapted for intermediate support of said conveyers, mounted on said journal pins and adapted to rest against the sides of said tubes.

3. Apparatus such as described, comprising a plurality of tubes for the flow of the material to be cooled, headers connecting them, each such tube formed in a plurality of sections, couplings connecting said sections having inwardly-projecting flanges, screw-conveyers within said tubes formed in corresponding sections and provided with journal-pins keyed to and connecting the sections, and free bearing bushings on said journal pins adapted for intermediate support of said conveyers and located opposite and arranged to bear against said inwardly-projecting flanges of said couplings.

4. Apparatus such as described, comprising a plurality of tubes for the flow of the ma-

terial to be cooled, formed each in a plurality of sections, couplings connecting said sections and having outwardly-extending centering lugs, jacket-tubes surrounding said first-named tubes, jacket-headers to which said jacket tubes are connected and through which said first-named tubes extend, said jacket headers provided with internal packing-abutment ribs interrupted for the longitudinal passage of the centering-lugs on said couplings, and packing means for forming joints between said headers and the tubes passing through them; and headers connecting said first-named tubes.

5. Apparatus such as described, comprising a plurality of tubes for the flow of material to be cooled, headers connecting them, screw conveyers within said tubes having suitable supporting bearings, and a thrust bearing for one of said screws, comprising a bearing collar secured to said screw and a washer of packing material located in a recess in the head of the corresponding header, and against which said collar bears.

In testimony whereof I have signed this specification in the presence of two subscribing witnesses.
